(57) **CLAIM**

The ornamental design for a knife blade, as shown and described.

DESCRIPTION

FIG. 1 is a left side perspective view of a knife blade showing my new design;

FIG. 2 is a left side view of the knife blade;

FIG. 3 is a right side view of the knife blade;

FIG. 4 is a right side perspective view of the knife blade;

FIG. 5 is a front view of the knife blade;

FIG. 6 is a back view of the knife blade;

FIG. 7 is a bottom view of the knife blade;

FIG. 8 is a top view of the knife blade;

FIG. 9 is a left side view of the knife blade shown in conjunction with a knife;

FIG. 10 is a left side perspective view of a minimally modified form of the knife blade;

FIG. 11 is a left side view of the minimally modified form of the knife blade;

FIG. 12 is a right side view of the minimally modified form of the knife blade;

FIG. 13 is a right side perspective view of the minimally modified form of the knife blade;

FIG. 14 is a front view of the minimally modified form of the knife blade;

FIG. 15 is a back view of the minimally modified form of the knife blade; and,

FIG. 16 is a bottom view of the minimally modified form of the knife blade.

The broken lines of the knife blade depict parts of the knife blade that form no part of the claimed design. The broken lines of the knife blade depict the environment and form no part of the claimed design. The modifications in FIGS. 10 through 16 that are confined to unclaimed aspects of the knife blade do not affect the appearance of the claimed design.
